ABSTRACT

A process of purifying the exhaust emissions of an automotive engine, by passing the exhaust gas through a series of tanks containing a mixture of saline solution and a solution of Tri-Sodium Phosphate. The tanks may be located adjacent the engine section of the automobile and behind the front headlight and fender section for optimum cooling.

AUTOMOTIVE ENGINE EXHAUST PURIFIER

SUMMARY OF THE INVENTION

This invention relates to a process for purifying the exhaust emissions of an automotive engine, by passing the exhaust gases through a series of tanks containing a wash solution, and particularly a solution which is a mixture of a saline solution and Tri-Sodium Phosphate.

The exhaust gases from the engine are passed into a primary tank which is filled to the level of three-quarters of its height with the wash solution by a supply tank of the solution. Vents from the primary tank lead excess vapor, or overflow liquid to two additional auxiliary tanks containing the wash solution. The auxiliary tanks are vented for the relief of any excess pressure. The level of solution in the primary tank is maintained by gravity flow of the solution from the supply tank, in accordance with the control of a metering float located in the primary tank. The tanks are preferably set up in linear order with each of the two auxiliary tanks located directly behind the primary tank. A double set of tanks as described above may be mounted in an automobile, with one complete system mounted in a front fender on one side of the automobile, and the other system of tanks mounted in the other front fender.

BRIEF DESCRIPTION OF THE DRAWING

The objects and features of the invention may be understood with reference to the following detailed description of an illustrative embodiment of the invention, taken together with the accompanying drawing which is a process sketch of the invention.

DESCRIPTION OF THE PREFERRED EMBODIMENT

Turning now descriptively to the drawing, in which similar reference characters denote similar elements throughout the views the drawing illustrates the exhaust purifying system which comprises supply tank 10 containing a mixture of a saline solution and Tri-Sodium Phosphate solution 11. The solution 11 flows by gravity through supply pipe 13 to the primary tank 20. Metering valve 12 in supply pipe 13 controls the flow of liquid 11 to the primary tank 20 in accord with a float level detecting means in the primary tank 20 which limits the height of the solution 11 in the primary tank 20 to three-quarters of the height, h , of the primary tank. Overflow outlets 24 in the supply tank 20 are connected by pipes 25 to two auxiliary tanks 30, each of which is equipped with air and gas vents 31 and liquid overflow outlets 32.

The lower sections of all tanks are lined with remov-

able filter elements 22 which retain the solid particles that have precipitated out of liquid 11 when the liquid 11 is released from the tanks through the individual drain pipes 23 located at the bottom of each tank. All tanks are enclosed with removable covers 26.

Exhaust gas 14, from the engine, is led through the exhaust manifold 15 into the primary tank 20 below the normal level of the solution 11 in tank 20. Undecondensed gas vapor and liquid overflow from primary tank 20 exits through overflow outlets 24 and pipes 25 to either of the two auxiliary tanks 30, where the overflow product 27 from the primary tank 20 is led below the normal level of the liquid 11 in the auxiliary tanks 30.

Undecondensed vapor exits the auxiliary tanks 30 through outlets 31 located in the sides of the tank. Overflow outlets 32 are also provided for excess liquid in the sides of the tanks 30.

The primary and auxiliary tanks may be cooled by being placed in the airstream of the moving vehicle, preferably under a front automobile fender. The wash solution of a mixture of saline solution and Tri-Sodium Phosphate dissolves some of the solids in the exhaust emissions, while much of the gas vapors are condensed in the tank system.

Since obvious changes may be made in the specific embodiment of the invention described herein, it is indicated that all matter contained herein is intended as illustrative and not as limiting in scope.

Having thus described my invention, what I claim as new and desire to secure by Letters Patent of the United States is:

1. A process of purifying the exhaust emissions of an automotive engine by passing the exhaust gases through a series of tanks containing a mixture of a saline solution and a solution of Tri-Sodium Phosphate, in which the engine exhaust gas is passed into the said liquid solution, below the solution level, in a primary tank, said solution being maintained to a minimum level in the primary tank by a valve in the supply line leading from a supply tank to the primary tank, so as to maintain a uniform level of solution in the primary tank, in which an overflow outlet in the primary tank located above the solution level is connected to a pipe leading below the level of a similar liquid solution in an auxiliary tank, said liquid solution in the auxiliary tank being otherwise not connected to the liquid solution of the primary tank so that each tank may be drained independently of each other, with the primary tank and the auxiliary tank located so as to be cooled by an airstream generated when the vehicle in which they are mounted is in a moving status.
